UNITED STATES PATENT OFFICE.

ABRAHAM GOODMAN, OF NEW YORK, AND JACOB GOODMAN, OF BROOKLYN, NEW YORK.

HAIR WAVER.

Application filed October 4, 1928. Serial No. 310,217.

This invention relates to improvements in hair wavers adapted for application to hair for imparting a wave thereto.

Objects.

5 Among the principal objects which the invention has in view are: to provide an article of light weight; to construct the article for convenient application in service; to provide 10 a novel and improved pivot for use in connection with the members thereof; to reduce the number of parts; and to simplify and cheapen the construction.

Drawings.

15 Figure 1 is a perspective view showing a hair waver constructed in accordance with the present invention and applied to the hair as in service;

20 Figure 2 is a perspective view of a hair waver constructed according to the present invention showing the parts thereof in open position for application to the hair;

25 Figure 3 is a plan view of the hair waver with the parts in closed position as in service;

30 Figure 4 is a side elevational view corresponding to Figure 3;

Figure 5 is a cross-sectional view through 35 the hair waver showing the hair arranged thereon for producing the wave.

Description.

In detail, the invention is embodied in a 40 construction which comprises a member 10, preferably composed of a wire-like element of light weight, such as aluminum. The element is pivoted as at 11 to another member which is also composed of a wire-like element, of a light metal such as aluminum, having an end loop, 13, and spaced parallel 45 portions, 12, extending therefrom. The ends of these parallel portions terminate in coils 14 in proximity and adjacent to each other.

50 The pivoted end of the element 10 also terminates in a coil 15, and a rivet 16 is extended through the coils and is headed over to maintain and retain the coils together as shown in Figure 3 and to form a pivot for the two members of the waver. The two members are adapted to swing relative to each other on this pivot and may open up as shown in Figure 2 or close as shown in Figure 4.

55 The loop end 13 preferably extends ob-

liquely to the parallel portion 12 and has arched portions 17 approaching each other at the entrance through which the free end of the element 10 is snapped, when moved to closed position into the loop. The arched portions form a resilient lock for maintaining the parts in closed or locked position as shown in Figure 4. The free end of element 10 is also deflected as at 18 to facilitate its entry and maintenance in the loop 13 in 60 closed position in service.

The rivet, 16, is preferably raised with respect to the parallel portions so that the member 10 is elevated with respect to portions, 12, when the waver is closed. The parallel portions and member, 10, are also preferably curved or bowed, as shown in Figure 4, and the curvature of 10 is somewhat greater than that of the portions, 12.

65 In the application of the waver to the hair in practise the two members of the waver are opened up as shown in Figure 2 and the hair is arranged neatly over the member 10. The members are now moved on the pivot into closed or locked position, the part 10 passing 70 between the spaced parallel portions 12 and the hair is formed into a wave as indicated in Figure 5, extending over the part 10 and under the portions 12. The hair waver may be left on the hair and as it is locked in its 75 closed position, there is no danger of the hair loosening or the waver falling out of the hair. The waver may be retained in the hair for any desired time and until the wave has been acquired in the hair.

80 The construction described is characterized by its simplicity, cheapness, light weight and efficiency in service. The novel pivot construction is a nice feature as it provides for simplicity, rigidity and produces a 85 sturdy light article. The invention also provides for a construction of relatively few parts, and there is little danger of the parts becoming disassembled in service.

85 I claim:

1. An article of the class described comprising a member formed of a wire like element bent to form an end loop with parallel portions extending from said end loop and terminating in adjacent coiled ends, a second 105 member having a coiled end positioned between the coiled ends of the first member, a rivet extending through all of said coiled ends for maintaining the same attached as in service and providing a pivot, said members be- 110

ing adapted for relative pivotal movement on said rivet so that the second member may be moved between the parallel portions of the first members and its free end into and out of 5 locking engagement with the loop, said loop extending obliquely from the parallel portions, and said rivet being raised with respect to said parallel portions, so that the second member has an elevated position with respect 10 to the parallel portions when in locking engagement with the loop.

2. An article of the class described comprising a member formed of a wire like element bent to form an end loop with parallel 15 portions extending from said end loop and terminating in adjacent coiled ends, a second member having a coiled end positioned between the coiled ends of the first member and

terminating in an oblique locking portion, a rivet extending through all of said coiled 20 ends for maintaining the same attached as in service and providing a pivot, said members being adapted for relative pivotal movement on said rivet so that the second member may be moved between the parallel portions of 25 the first member and its obliquely extending free end into and out of locking engagement with the loop, said loop extending obliquely from the parallel portions, and said rivet being raised with respect to said parallel 30 portions, so that the second member has an elevated position with respect to the parallel portions when in locking engagement with the loop.
